(57) **CLAIM**

The ornamental design for an exhalation port for a breathing circuit, as shown and described.

DESCRIPTION

FIG. 1 is a front, left side and top perspective view showing a front side of an exhalation port for a breathing circuit. FIG. 2 is a rear, right side and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The dash-dot broken lines illustrate the bounds of the claim and form no part of the claimed design. All other broken lines illustrate portions of the exhalation port for a breathing circuit and form no part of the claimed design.

1 Claim, 4 Drawing Sheets
